CLARENCE A. BATES, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

1,255,126.

Specification of Letters Patent.

Patented Feb. 5, 1918.

Application filed March 27, 1917. Serial No. 157,695.

To all whom it may concern:

Be it known that I, CLARENCE A. BATES, a citizen of the United States of America, and residing at Bridgeport, in the county of 5 Fairfield and State of Connecticut, have invented a certain new and Improved Electric Switch, of which the following is a specification.

My invention relates to electric switches 10 and particularly to switches of the two-way type, the object of my invention being to provide a three point push button switch of simplified and improved construction.

In the accompanying drawings, 15 Figure 1 is a plan of the switch in which my invention is embodied;

Fig. 2 is a section on the line 2—2, Fig. 1;

Fig. 3 is a broken side elevation showing the switch mechanism; and

20 Fig. 4 is a diagram illustrating the mechanism and the installation for which it is particularly designed.

The present switch is of the push button type and comprises a cup-shaped insulating body 10, the open face of which is spanned by a yoke 11 through which the push buttons 12 pass and the ends of which are slotted at 13 to receive the securing screws by which the switch is mounted in an outlet 25 box of common type (not shown). Within the switch chamber are arranged the standards 14, 15 and 16, the two latter at opposite corners at one end of the chamber, and the standard 14 at the opposite end of the chamber and in line with standard 15. Binding screw 17, at the upper end of standard 14, secures the line wire connection X, while binding screws 18 and 19 secure the branch wires O, P, leading to a three-point switch 30 S, the terminal 20 of which connects with the other line wire Y. A lamp 21 is arranged in the circuit beyond the terminal 20. The installation for which the switch is specially intended is shown in Fig. 4 and 35 is common for controlling a hall light from either the entrance hall switch or from the second story switch S. To the standard 14 is secured a switch terminal 22 having two contact wings 23, 24, adapted to make connection with the switch blade 25 in either 40 of its two positions. A switch terminal 26 is mounted on the standard 15 and is engaged by one end of the switch blade 25 when its opposite end is engaged with

the wing 23 of the terminal 22. The double blade 25 is electrically and mechanically connected by an integral bridge piece 27 with the co-operating single blade 28, which extends only on one side of the common axis 29 and co-operates with the 55 switch terminal 30 mounted upon the standard 16. It is obvious that when the blade 25 is in contact with the arm 24 of the terminal 22, the current flows through the bridge 27 to the blade 28 and establishes 60 connection from the terminal 24 to the terminal 30. In either position of the switch bar therefore the line X is connected to one or the other of the terminals 31, 32, of the co-operating switch S. If the latter be of 65 like construction to the present, the control of the hall light from either switch is readily understood.

The mechanism for operating the switch bar is of well known construction and is 70 not illustrated in detail here further than to show the usual rocker bar 33 and spring-pressed escapement plate 34.

The construction illustrated eliminates 75 from the three-point switches now commonly 80 in use, not only one of the switch terminals but also portion of one of the switch blades and thus effects a very appreciable saving 85 in relatively expensive metal parts. The switch bar itself is readily made by a stamping and pressing operation which greatly economizes the cost of this element of the switch as well as eliminates any danger of 90 a failure of connection between the two switch blades. The Y-shaped terminal 22 is as 95 readily connected to the standard 14 as a single terminal by a simple riveting operation. While the form of this terminal may be modified in various ways, I prefer that illustrated.

Various modifications of construction and 95 variation of detail will readily occur to those skilled in the art without departing from what I claim as my invention.

I claim:—

1. In an electric switch comprising a line terminal and two branch terminals, a two position oscillating bridge member connecting at different points with the line terminal in the different positions of the switch 105 and alternately with the branch terminals, a switch spring operatively connected to the bridging member and push buttons for ener-

gizing said spring to move the bridging member with snap action to its successive positions.

2. An electric switch comprising a line terminal and two branch terminals, a two position switch bar having a double arm blade connecting with the line terminal in both positions and with one of the branch terminals in one position of the switch, and 10 having also a one arm blade connecting with the other branch terminal in that position of the switch in which the two arm blade is out of contact with the first mentioned branch terminal, together with a 15 push button mechanism for shifting the switch bar from one position to the other.

3. In an electric switch having a line terminal and two branch terminals, a novel two position switch bar comprising a pair 20 of rigid, spaced blades adapted to engage alternately their respective branch switch terminals, while one of said blades is adapted to engage the line terminal in both positions of said bar, together with a connect-

ing bridge extending between said blades 25 and intergral therewith, for electrically and mechanically connecting said blades together.

4. In an electric switch having a line terminal and two branch terminals, a novel 30 two position switch bar comprising a pair of spaced blades and a connecting bridge, said bridge and blades being integral, and one of said blades comprising a pair of contact arms, and the other being a single 35 arm, the former blade being adapted to engage the line terminal, in both positions of the bar, and one of the branch terminals in one position of the bar, while the single arm blade is adapted to engage the other 40 branch terminal in the other position of the bar.

In testimony whereof I have signed my name to this specification.

CLARENCE A. BATES.
